US0D1099148S

(12) **United States Design Patent** (10) **Patent No.:** **US D1,099,148 S**
(45) **Date of Patent:** **** Oct. 21, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Mario Azzi**, Smithtown, NY (US);
Anton Davyдов, Gilroy, CA (US);
Alan C. Dye, San Francisco, CA (US);
Nicholas Felton, Cupertino, CA (US);
Aurelio Guzmán, San Jose, CA (US);

CLAIM

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 shows a display screen or portion thereof with graphical user interface showing our new design; and, FIG. 2 shows another embodiment thereof.

The peripheral dashed broken lines illustrate a display screen or portion thereof, and form no part of the claimed design.
